(57) **CLAIM**

The ornamental design for a LED dash/deck light, as shown and described.

DESCRIPTION

FIG. 1 is a rear view of a LED dash/deck light showing my new design;

FIG. 2 is a bottom view thereof;

FIG. 3 is a front view thereof;

FIG. 4 is a left side view thereof;

FIG. 5 is a perspective view thereof; and

FIG. 6 is a right side view thereof; and,

FIG. 7 is a top view thereof.

The broken line showing is included for the purpose of illustrating and forms no part of the claimed design.

The nature and intended use of the article in which the design is embodied is that of a LED (light emitting diode) dash/deck light for use on a dashboard or deck of a vehicle and the like.
